ATTORNEY.

UNITED STATES PATENT OFFICE.

DAVID Z. EVANS, OF PHILADELPHIA, PENNSYLVANIA.

GAS-BURNER.

SPECIFICATION forming part of Letters Patent No. 394,645, dated December 18, 1888.

Application filed December 20, 1887. Serial No. 258,476. (No model.)

To all whom it may concern:

Be it known that I, DAVID Z. EVANS, a citizen of the United States, residing in the city and county of Philadelphia, State of Pennsylvania, have invented a new and useful Improvement in Gas-Burners, which improvement is fully set forth in the following specification and accompanying drawings.

My invention consists of a gas-burner having means for supplying the same with heated air, as will be hereinafter set forth and claimed.

It further consists in the combination and arrangement of parts, as hereinafter described and claimed.

Figure 1 represents a vertical section of a gas-burner embodying my invention. Fig. 2 represents a horizontal section thereof in line *xx*, Fig. 1.

Similar letters of reference indicate corresponding parts in the two figures.

Referring to the drawings, A represents a burner, which is of the form of an annulus, with openings or jets at top and supply-pipes B connected at bottom, the latter being attached to the main pipe C.

Encircling the annulus or burner A and firmly secured thereto is a perforated plate, D, which supports the chimney E and guard F. Depending from the plate D and inclosing the lower part of the burner is a chamber, G, from the center of which rises a flue, H, the latter entering a shell, J, which is secured to a button, disk, or deflector, K, and depends therefrom into the space within the inner wall of the annulus or burner A. The deflector K, located above the burner A, is fitted to a screw-rod, L, which rises from the top wall of the pipes B, passes through the flue H, extends above the deflector K, and has fitted to its top a nut or screw-button, J'.

Resting on the deflector is a hollow cylinder or shell, M, which is held in position by the nut or button J' on the top thereof.

It will be seen that when the burner is lighted the flame assumes the form shown by the dotted lines, or approximately so. The cylinder M and deflector K are heated by the flame, the heat being also transmitted to the flue H and shell J. Air enters the flue H, rises to the top thereof, and is deflected into

the shell J, and, descending the latter, enters the bottom of the central space and is supplied to the interior of the flame. Some of the hot air after leaving the shell J enters the chamber G and, ascending the same, reaches the exterior of the flame through the perforated plate D and guard F. By these means the flame is supplied with large quantities of air in heated condition.

By rotating the deflector K it may be raised or lowered, the button J' being also raised or lowered as the core M follows the motions of said deflector K. By this provision the deflector may be set nearer to or farther from the top of the burner, and thus regulate the flame thereof.

Below the chamber G is an adjusting device, N, for the air admitted to the burner, the same being shown of the form of a concave plate, which has a central collar, the inner wall whereof is threaded for engagement with a threaded portion of the pipe C, whereby said plate may be raised or lowered for varying the space between the chamber N and said plate, so that greater or less quantity of air may be admitted to said space, and consequently to the flue H.

In the inner wall of the burner A, at the lower portion thereof, are perforations *a*, forming jets for the escape of gas at said inner wall, the same when ignited serving to heat the burner, and thereby cause heating of the gas prior to consumption by the burner proper.

Having thus described my invention, what I claim as new, and desire to secure by Letters Patent, is—

1. The combination of the supply-pipe B C, the annular burner A, the screw-rod L, the deflector K, adjustable thereon, the shell J, depending from said deflector, the flue H, entering said shell, the cylinder M above said deflector, and the button J' above said cylinder, substantially as described.

2. The burner A, with openings at the top, in combination with perforated plate D, the chimney E, and guard F on said plate, the deflector K, with support therefor and depending shell J, and the chamber G, with tube H rising therefrom and within the shell J, substantially as and for the purpose set forth,

3. The burner A, having openings at the

top and openings *a* at the bottom, in combination with the perforated plates D, the guard F, the deflector K, with support therefor, the depending shell J, and the chamber G, with tube H rising therefrom and within the shell J, substantially as and for the purpose set forth.

4. The inlet-pipe C and the burner A, in combination with the perforated plate D, the

deflector K, secured to the rod L, the depending shell J, the chamber G, with tube H, the latter entering said shell J, and the concave shell N, adjustable on said inlet-pipe, said parts combined substantially as described.

DAVID Z. EVANS.
